UNITED STATES PATENT OFFICE.

CHARLES W. WALKER, OF BRIDGEPORT, CONNECTICUT, ASSIGNOR TO
YOST WRITING MACHINE COMPANY, OF ILION, NEW YORK, A COR-
PORATION OF NEW YORK.

TYPE-WRITING MACHINE.

SPECIFICATION forming part of Letters Patent No. 739,626, dated September 22, 1903.

Application filed July 16, 1902. Serial No. 115,666. (No model.)

To all whom it may concern:

Be it known that I, CHARLES W. WALKER, a citizen of the United States, and a resident of Bridgeport, in the county of Fairfield and State of Connecticut, have invented certain new and useful Improvements in Type-Writing Machines, of which the following is a specification.

My invention relates to what may be termed "fractional-line-spacing devices for type-writing machines"—that is to say, a device which enables the platen to be rotated fractional degrees of the line-spacing attained with the aid of the ordinary line-spacing mechanism, in order that any desired portion of the platen may be brought to the printing-line, thus enabling the operator to readily fill in partly-printed blanks or to bring those portions of the paper to the printing-line which cannot be brought to such position with the ordinary line-spacing mechanism and without independently adjusting the paper on the platen. The device is likewise available as a means for distributing the wear over the entire surface of the platen instead of upon given lines, as is the case when the ordinary line-spacing mechanism alone is employed.

To the above ends my invention consists in the construction, arrangement, and combination of parts to be hereinafter described and claimed.

In the accompanying drawings, wherein like reference characters designate like parts in the various views, Figure 1 is a plan view of a platen-carriage, showing the application of my fractional-line-spacing device thereto. Fig. 2 is a transverse sectional view of the same on the line *v v* of Fig. 1 and looking in the direction of the arrow at said line. Fig. 3 is a detail fragmentary rear view of the ordinary and the fractional line-spacing mechanisms. Fig. 4 is a like view of the same, showing a different disposition of the parts. Fig. 5 is a vertical longitudinal sectional view of the same, the section being taken on the line *w w* of Fig. 1 and looking in the direction of the arrow at said line. Fig. 6 is a detail face view of the fractional-line-spacing mechanism, the view being taken from the left-hand

end of the platen. Fig. 7 is a detail perspective view of the fractional-line-spacing detent, spring, and carrier.

In various views parts are omitted to more clearly illustrate other parts of the structure.

The fractional-line-spacing device which constitutes the subject-matter of the present invention is shown applied to the platen-carriage of a Yost machine, though it should be understood that it may be applied to other descriptions of type-writing machines, and to this end various changes may be made in the construction and operation of the device without departing from the spirit of my invention.

The yoke-like frame 1 is connected at its freeends by screws 2 to an end plate 3, which is threaded to receive a screw 4, that has a cylindrical inner end 5, which is seated in a bearing 6 on the head 7 of the platen 8. The opposite end of the platen has rigidly secured thereto a finger-wheel 9, which is recessed for the reception of a bearing-stud 10, secured to the yoke 1 of the platen-frame, and which bearing-stud, with the cylindrical portion 5 of the screw 4, form journals on which the platen revolves. The platen-head 7 is provided with peripheral teeth 11 and end teeth 12 on the outer face thereof, the platen-head itself being secured to the core 13 of the platen by screws 14. The finger-wheel 9 and the platen-head 15 at the left-hand end of the platen-frame, to which the finger-wheel is rigidly connected, are secured in place by a headed rod 16, the head 16^a of which is seated within the recess 17 in the finger-wheel, whereas the opposite end of said rod 16 is threaded at 18 and takes in a threaded opening in the head 7, (see Fig. 5,) and thus secures the head 15 and finger-wheel 9 to the platen. The platen-head 15 and finger-wheel 9 are prevented from rotating with relation to the platen by pins 19, which are carried by the platen-head and project into openings in the core 13 of the platen. The end plate 3 of the platen-frame has bearings 20 and 20^a formed thereon for a rock-shaft 21, which is provided at its forward end with a finger-piece 22 and has a crank-arm 23 secured to its rear end. The arm 23 has piv-

oted thereto a line-spacing pawl 24, which is provided with a laterally-projecting pin 25, that extends through an opening in the arm 23 and constitutes a pivot for the line-spacing pawl. The pawl is maintained under tension of a spring 26, which is secured at one end 27 to the arm 23, and the opposite end of the spring is secured within the split portion 28 of the pin.

10 Mounted loosely on the shaft 21 is a controlling piece or stop 29, which is slotted at 30 for the reception of a pin 31, which projects laterally from an extension 32 of the bearing 20^a. This so-called "controlling-piece" 29 is provided with an abutting surface 33, against which the line-spacing pawl 24 is adapted to abut in its upward movement. The position of the controlling-piece 29 may be regulated by a spring-pressed engaging

15 pin 34, that is carried by the controlling-piece and is provided at its lower end with a contracted portion 35, that is adapted to be seated in any one of the three apertures 36 in the extension 32, and the contracted portion may be withdrawn from the apertures by the finger-piece 34^a, which contains the spring that normally maintains the pin in engagement. The adjustment of the controlling-piece 29 regulates the upward throw and position of

20 the line-spacing pawl 24 on its pivot, and thus regulates the line-spacing movement thereof, for single, double, and triple spacing.

25 The screw 4 in extending through the end plate 3 projects through a boss 37, that extends inwardly from the end plate and serves as a bearing for a carrier 38, that is concentric to the line-spacing ratchet-wheel. The carrier is adapted to turn on this bearing, and thus will turn on the same pivotal center that

30 the platen revolves on, and it is prevented from endwise movement in one direction by the end plate 3 and in the opposite direction by a sleeve 6^a, which surrounds the bearing 6. This carrier has screwed thereto at 38^a a

35 yoke-like spring 39, provided with ears 40, that constitute bearings for a detent-roller 41. This spring is effective to press the detent-roller 40 against the teeth 12 on the platen-head and to act in the capacity of the ordinary

40 detent-spring, which prevents an accidental displacement or rotation of the platen and for other purposes which will hereinafter appear. The carrier 38 is likewise provided with an arm 42, which is internally screw-

45 threaded for the reception of a screw or stop 43, which limits the downward movement of the line-spacing pawl 24 and which may be maintained in its adjusted position by a lock-nut 44. The carrier is likewise provided with

50 an abutment 45, against which the rear end of a screw 46 bears. This screw 46 is threaded in an internally-threaded bearing 47, that is carried by the end plate 3, and the forward end of the screw is provided with a knurled

55 head 48, by means of which the screw may be adjusted in its bearing. Lock-nuts 49 may

be provided on the rear portion of the screw, and said nuts are adapted to abut against the bearing 47, and thus limit the forward movement of the screw and prevent its withdrawal

70

75 A spring 50 is connected to and bears at one end against a screw 51, carried by the end plate, and bears at its opposite end 52 against the carrier 38. This spring bears intermediate its ends upon the front bar portion 1 of the platen-frame, thus maintaining a tension upon the carrier 38, which is effective to press the abutment 45 thereof against the rear end of the screw 46. The tension of this spring 50 is such as to prevent a movement of the carrier during the rotation of the platen. The tension may, however, be readily overcome by the adjusting-screw 46.

80 In the operation of the device for ordinary line-spacing a movement of the finger-piece 22 in the direction of the arrow adjacent thereto in Fig. 1 of the drawings is effective to move the line-spacing pawl from the position represented in Fig. 3 to that shown in Fig. 4, 90 and during this movement of the pawl the platen will be rotated the distance of one, two, or more teeth of its line-spacing wheel, as determined by the position of the controlling-piece 29. When the operator desires to 95 bring a portion of the platen to the printing-line that cannot be brought to such position with the aid of the ordinary line-spacing mechanism, the platen is rotated by the hand-wheel 9 or otherwise until that portion of the 100 paper where the writing is to be produced is adjacent to the printing-line. The fractional-line-spacing device may then be employed to move the platen independently of the ordinary line-spacing mechanism until the paper 105 has been brought to the proper position. The movement of the fractional-line-spacing mechanism is produced by turning the adjusting-screw 46, which is effective to turn the carrier in the desired direction, and the spring 39 and detent-roller will move therewith. This movement of the detent-roller while it bears upon the teeth 12 of the line-spacing wheel will carry the platen with it, thus bringing the paper to the desired 110 position. The movement of the platen by the fractional-line-spacing mechanism is indicated in Fig. 6, wherein the dotted line *a* 115 may be assumed to be the nearest approach to the proper position that can be obtained 120 with the aid of the ordinary line-spacing mechanism and without moving or adjusting the paper on the platen. With the parts in the position shown it is merely necessary to turn the adjusting-screw 46 by its knurled 125 head 48 from right to left, and the spring 50 will cause the carrier to turn a distance which corresponds to the movement of the adjusting-screw, thus turning the platen through the detent-roller and teeth 12 a like 130 distance to bring that part of the paper on which it is desired to write to the printing-

line indicated by the dotted line *b*. When the screw is turned in the opposite direction, it will turn the carrier against the tension of the spring 50 and force the detent to turn the platen in the opposite direction.

From the foregoing description it will be seen that the carrier 38 and the detent are positively moved on the pivotal center of the platen in one direction by the adjusting-screw 46 and in the opposite direction by the spring 50; that the detent at all times coöperates with the line-spacing ratchet-wheel; that when the platen and ratchet-wheel are turned either by hand or by the line-space lever and pawl the detent has no pivotal action, but simply bobs in and out of the notches of the line-space wheel, and that when the platen and line-space wheel are thus turned the pivotal movement of the detent and carrier in one direction will be prevented by the spring 50 and in the opposite direction by the screw 46. It will also be seen that the detent-carrier 38 is in the nature of a pivoted lever and that means are provided for moving it in opposite directions to effect fractional-line spacing of the platen. The said lever also comprises two arms, one arm 38^b of which is acted on by the spring 50 and the other arm 45 by the screw 46.

The fractional-line-spacing device is effective not only as such, but in the operation thereof it is also effective to change the lines of impact of the type upon the platen, thus evenly distributing the wear throughout the surface of the platen. It will also be observed that the detent-roller 41 acts as a detent-roller in the operation of the ordinary line-spacing mechanism and likewise constitutes a portion of the fractional-line-spacing device. It will be seen, furthermore, that no material changes are necessary to apply the fractional-line-spacing device, which constitutes the subject of the present invention, to the Yost type-writing machine.

While specific reference has been made to the fact that the line-spacing wheel shown and described is provided with peripheral teeth 11 as well as the edge teeth 12, the peripheral teeth in the present instance perform no function and may be omitted.

Many changes in detail construction and arrangement may be made without departing from the spirit of my invention, and of course any desired construction of line-space lever, pawl, and wheel may be employed instead of those herein shown and described.

Having described my invention, what I claim as new, and desire to secure by Letters Patent, is—

1. In a type-writing machine, the combination of a platen, line-spacing mechanism therefor and a fractional-line-spacing device which comprises pivoted bearing means which at all times bears against the platen and is adapted to remain fixed against a turning movement with said platen, and means for moving said

bearing means around its pivotal center to effect a movement of the platen for fractional-line spacing.

2. In a type-writing machine, the combination of a platen, line-spacing mechanism therefor, and a fractional-line-spacing device which comprises a spring-pressed detent which at all times bears against the platen and which is pivoted and adapted to move around the same pivotal center that the platen revolves on, and means for moving said detent around its pivotal center to effect a movement of the platen for fractional-line spacing.

3. In a type-writing machine, the combination of a platen, line-spacing mechanism therefor including a ratchet-wheel, and a fractional-line-spacing device which comprises a spring-pressed detent-roller which at all times bears against the ratchet-wheel, a pivoted support for said roller, and means for moving said support around its pivotal center to effect a movement of the platen for fractional-line spacing.

4. In a type-writing machine, the combination of a platen, a ratchet-wheel secured thereto, a line-spacing pawl which coöperates with said ratchet-wheel to effect an ordinary line-spacing movement of the platen, means for moving said pawl, a detent which bears against said ratchet-wheel, a pivoted spring for supporting said detent, which spring is adapted to remain fixed with relation to the movement of the ratchet-wheel or to be moved to effect a movement of the ratchet-wheel and platen, and means for moving said detent.

5. In a type-writing machine, the combination of a platen, a ratchet-wheel secured thereto, a line-spacing pawl which coöperates with said ratchet-wheel to effect an ordinary line-spacing movement of the platen, means for moving said pawl, a detent which bears against said ratchet-wheel and which is adapted to remain fixed with relation to the movement of the ratchet-wheel or to be moved to effect a movement of the ratchet-wheel and platen, a spring which maintains said detent in contact with the ratchet-wheel, means for positively moving said detent in one direction to effect a movement of the ratchet-wheel and platen, and a spring for moving the detent in an opposite direction, the tension of said moving spring being sufficient to resist the tendency of the detent to move with the ratchet-wheel when it is moved independently of the detent.

6. In a type-writing machine, the combination of a platen, a ratchet-wheel secured thereto, a line-spacing pawl which coöperates with said ratchet-wheel to effect an ordinary line-spacing movement of the platen, means for moving said pawl, a detent-roller which bears against said ratchet-wheel and which is adapted to remain fixed with relation to the movement of the ratchet-wheel or to be moved on the same pivotal center to effect a movement of the ratchet-wheel and platen, a spring

- which maintains said detent-roller in contact with the teeth of the ratchet-wheel, means for positively moving said detent-roller on said pivotal center in one direction to effect 5 a turning of the ratchet-wheel and platen, and a spring for moving the detent-roller on said pivotal center in an opposite direction, the tension of said moving spring being sufficient to resist the tendency of the detent-roller to turn on said pivotal center with the ratchet-wheel when the latter is moved independently of the detent-roller.
7. In a type-writing machine, the combination of a platen, a ratchet-wheel secured there- 15 to, a line-spacing pawl which coöperates with said ratchet-wheel to effect an ordinary line-spacing movement of the platen, means for moving said pawl, a spring-pressed detent which bears against the ratchet-wheel, a piv- 20 oted carrier for said detent, which carrier is adapted to turn on the same pivotal center that the platen revolves on, and means for turning said carrier in either direction, which turning means resists the tendency of the 25 detent to turn with the ratchet-wheel when the ratchet-wheel is rotated by the line-spacing pawl.
8. In a type-writing machine, the combination of a platen, a ratchet-wheel secured there- 30 to, a line-spacing pawl which coöperates with said ratchet-wheel to effect an ordinary line-spacing movement of the platen, means for moving said pawl, a bearing concentric to said ratchet-wheel, a carrier which is loosely 35 mounted upon said bearing, a yoke-spring secured to the carrier, a detent-roller carried by said spring and bearing on the teeth of the ratchet-wheel, and an adjusting-screw which coöperates with the carrier and affords 40 a movement thereof on its bearing.
9. In a type-writing machine, the combination of a platen-frame, a platen, a platen-head secured to the platen, a ratchet-wheel formed on the platen-head, a line-spacing pawl which 45 coöperates with the teeth of said ratchet-wheel to effect an ordinary line-spacing movement of the platen, means for actuating said pawl, a bearing on the platen-frame and concentric to the ratchet-wheel, a carrier loosely mount- 50 ed on said bearing, a spring secured to the carrier, a detent carried by the spring, which detent bears upon the teeth of said ratchet-wheel, an adjusting-screw carried by the platen-frame and coöperating with the carrier 55 to positively move it in one direction on its bearing, and a spring carried by the platen-frame and bearing against the carrier to effect a movement thereof on its bearing in an opposite direction, the tension of said spring 60 being sufficient to resist the tendency of the detent and carrier to move with the ratchet-wheel when the latter is moved backwardly.
10. In a type-writing machine, the combination with a platen and a regular line-spacing 65 mechanism therefor including a ratchet-wheel and a pivoted detent, of means for turning together the detent, ratchet-wheel and platen fractional-line-space distances.
11. In a type-writing machine, the combination of a platen, a ratchet-wheel secured thereto and a pivoted detent adapted to be turned and to turn the ratchet-wheel and platen fractional-line-space distances. 70
12. In a type-writing machine, the combination of a platen, a ratchet-wheel secured there- 75 to, a detent for said wheel mounted axially thereof, and means for turning said detent about its axis and thereby causing it to turn the ratchet-wheel and platen.
13. In a type-writing machine, the combination of a platen, a line-spacing pawl, a line- 80 space ratchet-wheel secured to the platen, a spring-pressed detent mounted axially of said wheel, means for holding said detent relatively stationary when the line-spacing pawl 85 is actuated, and means for turning said detent, ratchet-wheel and platen independently of said line-spacing pawl.
14. In a type-writing machine, the combination of a platen, a line-spacing ratchet-wheel, 90 a pivoted lever, a spring-pressed detent carried by said lever, and means for moving the lever in opposite directions so as to cause the platen to turn fractional-line-space distances.
15. In a type-writing machine, the combination of a platen, a line-spacing ratchet-wheel 95 fixed to rotate with the platen, a pivoted spring-pressed detent that bears at all times upon said ratchet-wheel, and means for adjusting said detent in opposite directions for 100 fractional-line spacing.
16. In a type-writing machine, the combination of a platen, a line-spacing ratchet-wheel fixed to rotate with the platen, a lever pivoted at the pivotal center of the platen, a spring- 105 pressed detent carried by said lever and bearing at all times on the line-spacing ratchet-wheel, and means for adjusting said lever in opposite directions to turn the platen through the detent for fractional-line spacing. 110
17. In a type-writing machine, the combination of a platen, a line-space wheel secured thereto, a line-spacing pawl, a detent for said wheel, a detent-carrier mounted axially of said wheel, a spring secured to said carrier 115 and supporting said detent, an adjusting-screw mounted in the platen-frame, a lug on said carrier to coöperate with said screw, and a spring acting on said carrier to cause said lug to bear against said screw, whereby the 120 detent remains relatively fixed when the line-space pawl is actuated but may turn about the axis of said carrier and ratchet-wheel when the adjusting-screw is manipulated and by such turning movement cause the ratchet- 125 wheel and platen to turn fractional-line-space distances.
18. In a type-writing machine, the combination of a platen, a ratchet-wheel that turns therewith, a detent that bears upon said 130 ratchet-wheel and is adapted to be turned therewith, a spring, the tension of which nor-

5 mally maintains said detent against movement in one direction with the ratchet-wheel, and means for overcoming the tension of said spring to turn the ratchet-wheel and platen through the detent.

19. In a type-writing machine, the combination of a platen, a ratchet-wheel that turns therewith, a pivoted detent that bears upon said ratchet-wheel, a spring, the tension of which normally maintains said detent against movement in one direction on its pivotal center, and adjustably-fixed means for resisting the pivotal movement of the detent in an opposite direction and overcoming the tension of said spring.

20. In a type-writing machine, the combination of a platen, a ratchet-wheel which turns therewith, a pivoted detent-carrier, a spring-pressed detent carried by said carrier, a spring

which resists the pivotal movement of the carrier in one direction and adjustable means which resist the pivotal movement of the carrier in the opposite direction.

21. In a type-writing machine, the combination of a platen, a ratchet-wheel arranged to turn therewith, a two-armed lever carrying a detent, a spring acting on one of said arms, and an adjusting device acting on the other of said arms.

Signed at the borough of Manhattan, city 30 of New York, in the county of New York and State of New York, this 11th day of July, A. D. 1902.
